164,290

HOLDER FOR STOCKINGS AND LINGERIE

James E. Donaldson, Chicago, Ill.

Application September 22, 1949, Serial No. 5,133

Term of patent 14 years

(Cl. D33—3)

To all whom it may concern:

Be it known that I, James E. Donaldson, a citizen of the United States and resident of Chicago, in the county of Cook and State of Illinois, have invented a new, original and ornamental Design for a Holder for Stockings and Lingerie, of which the following is a specification, reference being had to the accompanying drawing, forming a part thereof.

In the drawing, Figure 1 is a front elevational view of a holder for stockings and lingerie showing my new design;

I claim:

The ornamental design for a holder for stockings and lingerie, as shown.

JAMES E. DONALDSON.
